UNITED STATES PATENT OFFICE.

ALEXANDER B. KOKERNOT, OF NEW ORLEANS, LOUISIANA.

REFRIGERATOR ATTACHMENT FOR BEER-BARRELS.

SPECIFICATION forming part of Letters Patent No. 500,012, dated June 20, 1893.

Application filed January 11, 1893. Serial No. 458,050. (No model.)

To all whom it may concern:

Be it known that I, ALEXANDER B. KOKERNOT, a citizen of the United States, residing at New Orleans, in the parish of Orleans and 5 State of Louisiana, have invented new and useful Improvements in Refrigerator Attachments for Beer-Barrels, of which the following is a specification.

This invention relates to refrigerating attachments for beer barrels and other vessels wherein a tubular receptacle for the refrigerant is secured to the barrel heads by means of screw-threaded bushings, and the invention consists in the peculiar features of construction and novel combinations of devices for securing the bushings in place and for attaching the refrigerator tube thereto or detaching it therefrom, as hereinafter more fully set forth.

20 In the annexed drawings illustrating the invention Figure 1, is a central vertical section of a barrel with the refrigerator tube in position therein. Fig. 2, is a view of a device for use in assisting to support and hold the 25 barrel while the bushings for the refrigerator tube are being screwed into place. Fig. 3, is an inverted plan of the same. Fig. 4, is an elevation of the devices for supporting the barrel or vessel while inserting and removing 30 the refrigerator tube. Fig. 5, is a plan view of the same. Fig. 5^a is a detail sectional view of the upper end portion of one of the vertical arms. Fig. 6, is a plan of a ring forming part of said supporting devices. Fig. 7, is a 35 sectional view of said ring. Fig. 8, is a side elevation of a key for screwing the bushings into place. Fig. 8^a is a plan view of the same and Fig. 9, is a plan of a ring that may be used for confining the bushing, and Fig. 10 is a detail view of one of the vertical guide rods to more clearly illustrate the slot in its foot portion.

Referring to Fig. 1, the numeral 1, designates the barrel and 2 the barrel heads having holes in which the externally threaded bushings 3 are inserted. The bushings 3 have smooth interiors to receive the ends of the refrigerator tube 4, which is of sufficient length to extend through both bushings and project 45 outside the barrel heads. Each bushing 3 is provided at its outer end with a lateral flange

countersunk into the head of the barrel or vessel.

The ends of the refrigerator tube 4 extend outward beyond the bushings 3 and are externally screw-threaded for engagement with nuts 5. The outer edge of the interior circumference of each bushing 3 is sunken or chamfered and the adjacent portions of the nuts 5 are correspondingly sunken or chamfered whereby receptacles are formed for a packing 6 to form perfectly tight joints when the parts are in position. Over these nuts 5 are arranged sleeves or caps 7 having smooth exteriors and screw-threaded interiors. 65

The lower end of the refrigerator tube 4 may be internally screw-threaded to receive a bush or partition 8 that is externally screw threaded and provided with a faucet which may be opened when it is desired to discharge 70 any accumulated water or other liquid contents of the refrigerator tube.

For the purpose of facilitating insertion of the bushings 3 and the attaching and detaching of the refrigerator tube I employ the devices shown in Figs. 4, 5, 6 and 7. These devices comprise a vertical bushing 9 provided with three or more horizontal foot pieces 10 that are suitably secured to any convenient stationary support 11 as shown in Fig. 4. 75 Vertical guide rods 12 are detachably and adjustably connected to the foot pieces 10 by means of horizontal plates or shoes 13 which fit snugly to the horizontal surfaces of the foot pieces. These horizontal shoes or plates 80 13 have each an elongated opening 13^a through which a thumb screw 14 passes into an opening in the several foot pieces, whereby the guide rods 12 may be conveniently adjusted laterally. The guide rods 12 are each of such 85 length as to reach the largest diameter of the barrel or vessel, and at their upper ends each guide arm is provided with a clamp 15, which is adjusted to and from the barrel or vessel by means of a set screw 16, the clamp being 95 guided in its movements by pins 17 which slide in recesses therefor in the guide rods 12. The top edge of the bushing 9 is made smooth and even all around except at suitable points where recesses 18 are provided for a purpose 90 hereinafter explained.

When it is desired to screw the bushings 3

- into place in the heads of a barrel or other closed vessel, I place on the bushing 9, Fig. 4, a hollow cylinder or tubular cap 19, Fig. 2, having a square head or plate 20 at one end.
- 5 The tubular cap 19 is made to fit easily over the bushing 9 but without wobbling thereon. The greatest diameter of the square head 20, or the distance between diagonally opposite corners, may be the same as the diameter of 10 the outside of the barrel head, so that the corners of said plate or square head 20 will fit tightly within the chines, or, as shown in Fig. 3, the under side of the cap head 20 may be provided with pivoted ratchet arms 25 for engaging the chines. The inner walls of the tubular cap 19 are provided with lugs 21 to engage the recesses 18 in the top of the stationary bushing 9 and thus when the barrel is placed on the head 20 and securely clamped by the 15 guide arms 12 and ratchet arms 25 it will be firmly held and prevented from turning. To screw the bushing 3 in position, the cap 19 is slipped on to the stationary bushing 9 and the lugs 21 engaged in the notches or recesses 20 18 of the said stationary bushing. The barrel is then placed in position with its bottom head resting on the square head 20, the chines of the barrel extending down below said square head so that the ratchet arms 25 may 25 be engaged with the chines and thus prevent the barrel from circling either to the right or left. The clamps 15 at the upper ends of the guide rods 12 are now to be adjusted closely to the bilge of the barrel by means of the set 30 screws 16 so as to hold the barrel firmly. A bushing 3 can now be screwed into the upper head of the barrel by means of the key shown in Fig. 8, or other suitable instrument and then by unclamping the barrel its position 35 can be reversed and a bushing 3 be screwed in like manner into the other head.
- When it is desired to attach the refrigerator tube 4 to the barrel a nut 5 is screwed to one end of the refrigerator tube and over 40 the said end a head or ring 22, Fig. 6, is screwed up to the nut. This head or ring 22 is provided with lugs 23 which are now engaged in the recesses 18 of the stationary bushing 9, the headed cap 19 having been 45 previously removed. By means of this engagement of the head or ring 22 with the stationary bushing 9 the refrigerator tube 4, on which said ring is screwed, will be held securely in a vertical position. The packing 6 for the lower end of the tube 4 is then passed 50 down over the tube until it rests in the chamfered edge of the nut 5 and the barrel or vessel, to which the bushings 3 have been previously attached is then slipped over the refrigerator tube until the bushings 3 at both 55 ends of the barrel are fully engaged with said tube. The lower head of the barrel will then rest firmly on the ring 22 and the upper end of the refrigerator tube will project through 60 the bushing in the upper head of the barrel. To guide the lower head of the barrel to its

position on the bushing 9 and to hold it in a fixed position the guide rods 12 are adjusted sufficiently close to the barrel to permit the barrel being passed in and out freely and the 70 clamps 15 are then, by means of the set screws 16 forced against the vessel. Over the upper end of the tube 4 is now passed the packing 6 which is placed into the chamfered or recessed portion of the bushing. The upper 75 nut 5 and cap 7 are then screwed into place as tight as may be required. The barrel may then be lifted off from the bushing 9, the ring 22 removed from the end of the tube, and both ends of the tube being provided with caps the 80 barrel will be ready for service.

To detach the refrigerator tube from the barrel or vessel the caps 7 are removed, the ring 22 is screwed onto one end of the refrigerator tube, and the set screws 24 with which 85 said ring is provided are screwed down on the nut 5, whereby said nut is held fixed. The barrel is then placed upon the bushing 9, being guided thereto by the guide rods 12, the lugs 23 of the ring 22 are engaged in the 90 recesses 18 of said bushing 9 and the clamps 15 at the upper ends of the guide rods 12 are tightened against the barrel. The nut 5 on the upper end of the refrigerator tube is then unscrewed, the clamps are loosened and the 95 barrel or vessel is then lifted off the stationary bushing 9 and away from the refrigerator tube. The tube 4, with the lower nut 5 and ring 22 attached, is now removed from the bushing 9, after which said tube, nut and ring can be disconnected.

In Fig. 8 I have shown a key adapted for use in screwing on or unscrewing the nuts 5 and for screwing the bushings 3 into place. This key comprises a ring 26 from the top 105 side of which at equal distances apart four converging arms 27 rise and join in a vertical boss 28 having a hole through which a horizontal hand rod 29 is passed. The lower edge of the ring is provided at suitable points with 110 pins 30 that are adapted to be engaged in the recesses in the tops of the nuts 5 or in the recessed tops of the bushings 3; and the said pins being slightly shorter than the depth of said recesses the ring 26 will sit smoothly 115 and evenly on the nuts 5 or flanged bushings 3, as the case may be.

If desired, the exterior of the bushings 3 may be made smooth to within a short distance of their inner ends which may be slightly reduced in diameter and screw-threaded. In this case the flanged outer ends of the bushings need not be provided with recesses to receive an instrument for screwing them into position as they may then be easily driven into 125 the holes in the barrel heads and be secured by means of retaining rings 31, Fig. 9, on their inner screw-threaded ends. Packing material may, if desired, be interposed between the rings 31 and the inner sides of the barrel heads to which the said bushings and retaining rings are, of course, attached before the 130

heads are inserted in the barrels. I prefer to provide the rings 31 with radial arms 32 which afford a means for securely screwing the rings onto the bushings and which extend almost entirely across the inner surface of the barrel head and in contact therewith, thus increasing the security of the means for retaining the bushings in place.

What I claim as my invention is—

1. The combination with a support 11, and clamping rods 12, of the stationary bushing 9 having recesses 18 in its upper edge, of the tubular cap 19 provided with internal lugs 21 adapted to engage said recesses and the head or plate 20 on the upper end of said tubular cap and adapted to engage within the chines at the lower end of a barrel to support said barrel and prevent it from turning while being fitted with bushings for a refrigerator tube, substantially as described.
2. The combination with a support 11 the adjustable guide rods 12 provided with clamps 15, and the bushing 9 having recesses 18 in its upper edge, of the tubular cap 19 provided with the head or plate 20 and lugs 21, substantially as described.
3. The combination of the stationary support 11, the bushing 9 having recesses 18 in its upper edge and provided with feet 10 secured to said stationary support, a head adapted to engage the recesses of the bushing and the adjustable, vertically arranged guide rods

12 having clamps 15 at their upper ends, substantially as described.

4. The combination with a support 11, and 35 clamping rods 12, of the stationary bushing 9 having recesses 18 in its upper edge, of the ring 22 having lugs 23 and set screws 24, substantially as and for the purposes described.

5. The combination with a central stationary bushing 9, and a head adapted to engage the bushing of a series of adjustable, vertically arranged guide rods 12 arranged around said bushing and provided with clamps 15 at their upper ends, said bushing adapted to engage devices for supporting a barrel while a refrigerator tube is fitted thereto or removed therefrom, substantially as described.

6. The combination with a support 11, and 50 clamping rods 12, of the stationary bushing 9 having its upper edge provided with recesses 18, of the tubular cap 19 provided internally with lugs 21 adapted to engage said recesses and having a head 20 provided with ratchet arms 25 to engage within the chines of a barrel, substantially as described.

In testimony whereof I have hereunto set my hand and affixed my seal in presence of two subscribing witnesses.
